UNITED STATES PATENT OFFICE.

WILLIAM B. BARTLEY, OF MERIDEN, CONNECTICUT, ASSIGNOR TO THE J. D. BERGEN CO., OF MERIDEN, CONNECTICUT, A CORPORATION.

DESIGN FOR A CUT-GLASS VESSEL.

Application filed November 16, 1921. Serial No. 515,720. Term of patent 3½ years.

To all whom it may concern:

Be it known that I, WILLIAM B. BARTLEY, a citizen of the United States, residing at Meriden, in the county of New Haven and State of Connecticut, have invented a new, original, and ornamental Design for a Cut-Glass Vessel, of which the following is a specification, reference being had to the accompanying drawing, forming part thereof.

Figure 1 is a side view of a cut-glass vessel showing my design.

Figure 2 is an underside view of the same.

I claim:

The ornamental design for a cut-glass vessel, as shown.

WILLIAM B. BARTLEY.

Witnesses:

JOHN B. LACAVA,
MARY E. HYLAND.
